UNITED STATES PATENT OFFICE.

HARRY COLLINS, OF SWEETWATER, TEXAS.

BATTERY-ELEMENT REMOVER.

Application filed May 31, 1922. Serial No. 564,781.

To all whom it may concern:

Be it known that I, HARRY COLLINS, a citizen of the United States, residing at Sweetwater, in the county of Nolan and 5 State of Texas, have invented new and useful Improvements in Battery-Element Removers, of which the following is a specification.

This invention relates to a battery element remover, comprising tongs of a type adapted for simultaneously gripping the opposed posts of the element plates, whereby an element as a unit may be readily and conveniently withdrawn from its cell or inserted therein. The object of the invention 10 is to provide a device of this character which is simple of construction, convenient, reliable and efficient in action, capable of being cheaply manufactured, and adapted to be employed to facilitate the operation of removing and replacing a battery element as 15 well as carrying the same from place to place.

The invention consists of the features of 20 construction, combination and arrangement of parts, hereinafter fully described and claimed, reference being had to the accompanying drawing, in which:—

Figure 1 is a side elevation of a portion 25 of a battery cell, showing the removing tongs engaged with the cell posts in position for operation.

Figure 2 is an end elevation of the same.

Referring to the drawing, 1 designates 30 a battery cell of any ordinary construction, having the vent 2 and the projecting posts 3 on opposite sides of said vent, which posts are connected with the battery plates composing the battery element and are adapted 35 to be coupled in practice by the usual removable post connector. The posts 3, which project outwardly through the cell cover, are ordinarily made of lead or other similar 40 comparatively soft metal.

45 In carrying my invention into practice I provide an element remover comprising a pair of tongs 4 of novel construction. These tongs consist of a pair of substantially U-shaped or bail-shaped handles 5 which are substantially counterparts in form and construction. Each of these handles embodies, as shown, a pair of parallel side arms 6 connected at their upper or outer ends by a cross bar 7 forming a handle or grip member. 50 The handles 5 are adapted, when the jaws of the device are in closed position, to lie

60 closely together and in parallel relationship, as illustrated in Figure 2.

The side bars 6 of the respective handles 5 are provided at their lower or free ends with jaws 8 connected with said arms by angularly disposed portions 9. These angularly disposed portions 9 of the two handles project in opposite directions, and the said angularly disposed portions of the arms at 65 the opposite sides of the handles are arranged in crossed relationship and pivotally coupled, as indicated at 10, by means of bolts, rivets or other suitable coupling means.

When the handles of the tongs are closed the 70 respective pairs of jaws at the opposite sides of the tool are adapted to lie in parallel relationship, and said jaws are provided at their outer or free ends with inwardly projecting substantially V-shaped gripping teeth 11, which terminate in comparatively sharp biting edges. The pairs of jaws of the tool 75 are so spaced that the tool may be arranged to bridge across the space between the posts 3 and over the vent 2 so as to bring the jaws 8 of the respective pairs on opposite sides of the 80 respective posts, the arrangement being such that the jaws may be opened to allow them to be placed in gripping position on opposite sides of the posts and then closed to grip the posts. The posts 3 being made 85 of lead or other comparatively soft metal, it will be understood that the sharp biting edges of the teeth 11 will bite or sink thereinto, thus allowing a firm connection to be 90 obtained on the closing of the jaws, whereby a positive grip is ensured to obviate any liability of the battery element slipping out of engagement with the tool, when the handles 5 are closed, thus enabling the battery element to be raised and lowered and 95 handled with safety and surety and without liability of dropping and damaging the same.

When it is desired to remove a battery 100 cell from the battery casing, after the casing has been unsealed and the cover sections removed, the handles 5 of the device are held in the hand and the grip members 7 spread so as to spread the jaws 8 the proper distance apart, the device then being disposed in the position shown in Figure 1 with the jaws arranged on opposite sides of the posts 3, and the handles are then closed together to close the jaws and cause the biting edges 105 of the teeth 11 thereof to engage and sink into the material of the posts. The device 110

- may then be held in a single hand of the operator, and a firm connection between the extractor and the battery element will be afforded to enable the element to be drawn with one hand, while the other hand is employed for other purposes. In a similar manner the jaws may be engaged with the battery posts whenever it is desired to reinsert the battery element within its cell.
- It will be observed that the construction of the tool handles is such that the handle members lie in parallel relation, thus disposing the grip 7 so that the jaws may not only be held closed but the tool employed as a convenient device for transporting the battery element from place to place as required for repairs or other purposes. The construction is also simple and adapts the

device to be manufactured and sold at a comparatively low cost.

Having thus fully described my invention, I claim:

A battery element remover comprising a pair of tongs, each consisting of a looped handle member embodying side arms and a transverse grip portion, the free ends of said arms being crossed and pivotally connected and provided with terminal jaws, said jaws being arranged parallel to said arms and being of less length than the body portions of the arms, the free ends of said jaws being provided with sharp edge biting projections extending across the inner faces thereof.

In testimony whereof I affix my signature.

HARRY COLLINS.
